UNITED STATES PATENT OFFICE

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY

ARTICULATED CAR

Application filed December 9, 1930. Serial No. 501,019.

This invention relates to articulated cars of the type in which a single truck, known in the art as a pivot truck, is arranged beneath and supports the adjacent end portions of two car bodies.

One object of this invention is the provision of an articulated car in which the adjacent end portions of two car bodies are arranged in substantially abutting relation whereby to transmit buffing shocks from one body to the other; the adjacent end portions having means arranged therein for preventing excess sidewise and vertical shifting of the bodies.

Another object of this invention is the provision of an articulated car having a plurality of car bodies the adjacent end portions of which are arranged in substantially abutting relation and which are supported respectively by truck bolsters.

A further object of this invention is the provision of an articulated car comprising a plurality of car bodies, and a truck for supporting the adjacent end portions of said bodies, said truck being provided with a pair of independently functioning bolsters, one each for supporting a car body end portion.

A still further object of this invention is the provision of a new and improved body center casting for an articulated car.

Other objects and advantages of this invention will be apparent from the following description taken in conjunction with the accompanying drawing in which:

Fig. 1 is a top plan view of the invention, the view showing a portion of one car body and having certain parts broken away and other parts shown in section.

Fig. 2 is a sectional view showing the articulated joint of the present invention.

Fig. 3 is a view taken on the line 3—3, Fig. 1, and

Fig. 4 is a fragmentary sectional view showing the mounting for the foot plate used with the present invention.

In the drawing a complete truck is not shown as the specific construction thereof forms no part of the present invention. Only such parts of the truck as are necessary to an understanding of this invention have been

illustrated, and it is to be understood that these parts may be associated with a car truck having any preferred or desired form.

Referring now more particularly to the drawing, in which similar characters of reference designate similar parts in the several views, the present invention provides for articulating a plurality of car bodies, a portion of one thereof being indicated generally at A, but inasmuch as the specific construction of the bodies is not a part of the present invention aside from those parts specifically illustrated and described hereinafter, the same is not shown in detail. The bodies of course are provided with a suitable underframe and in the instance shown the underframe includes spaced channels 2 forming center sills between which are arranged body center castings 4. Said castings are preferably connected to the channels 2 by suitable fasteners such as rivets or the like, and their forward ends project beyond the ends of the car bodies.

The body center castings each comprises a body portion having a top surface 6, bottom 8, side walls 10 and a front wall 12; the castings being hollow and reinforced by suitable stiffening ribs 14.

The front wall 12 of the casting tapers from the side walls toward the longitudinal center line of the casting to define a buffing area 16 and, as can be seen in Figs. 1 and 2, the areas 16, when the bodies are assembled, are closely adjacent each other whereby buffing shocks may be transmitted from one body to the other.

Formed with and depending from the forward ends of castings 4 are body center bearings 18 which are substantially cylindrical in shape and are provided with concentric recesses 20. The body center bearings extend into truck center plates 22 carried by truck bolsters 24. The truck center plates are circular in shape and are each provided with an apertured concentrically arranged projection 26 positioned in the before mentioned recesses 20.

From the description thus far it will be apparent that each body may swivel horizontally relative to the other due to the connect-

ed body and truck center bearings. It is further apparent that pulling stresses are transmitted from the bodies to the truck through the connected body center bearings and truck center plates. It is necessary however to provide for preventing excessive relative horizontal and vertical shifting of the car bodies and still permit a certain amount thereof in accordance with variations in track structure. To this end, the extreme forward ends of the castings are provided with horizontally arranged recesses 28 which align when the bodies are assembled and which receive a restraining element 30 in the form of a bar or the like, apertured adjacent each end as at 32. For retaining the bar in position pins 34 are provided which extend through the ends of the castings 4 and through the bar and the projections 26 and into the upper walls 36 of the bolsters. As shown in Fig. 2, the apertures 32 in the bar 30 are large compared to the pins 34 to permit a certain amount of looseness and thus obtain the necessary flexibility of parts. To permit the required relative swiveling of the car bodies the recesses 28 gradually increase in width from the rear thereof to the ends of the castings. Such arrangement, it will be apparent, permits a certain amount of relative sidewise shifting of the bodies but prevents excessive relative sidewise shifting.

Due to breaks in track grades it is necessary to permit some vertical shifting of the bodies and to this end the depth of the recesses 28 varies as shown clearly in Fig. 2; the depth at the extreme forward end of the castings being the greatest. This will permit a sufficient relative vertical shifting of the bodies but obviously will prevent excessive relative vertical shifting. The bar 30, it is to be understood is not designed to transmit pulling stresses from one body to the other and hence is not a draw bar nor the equivalent thereof. The function of the bar 30 is to prevent excessive relative vertical and sidewise shifting and necessarily the bar must be relatively loose in the aligned recesses 28.

The adjacent end portions of the car bodies are provided with door openings (not shown) and to permit passengers to pass from one body to the other foot plate 38 is provided which bridges the space between the adjacent end portions of the bodies; the ends of said foot plate underlying arcuate shaped threshold castings 40 secured to the bodies.

The foot plate 38 is supported in a fixed position relative to the bodies. In other words, swiveling of the bodies is relative to the foot plate. The foot plate is supported by the bolsters 24 and as shown in Fig. 4 the bolsters 24 are each provided with a pair of brackets 42 which support springs 44 on which the foot plate is mounted; the latter being held against the tension of the springs by bolts 46 which extend through the brackets 42 and

foot plate 38 and are secured in position by nuts 48.

From the above description it is believed that the construction shown in the drawing will be fully understood by those skilled in the art. In operation the bodies swivel independently of each other due to the connected body and truck center bearings; the adjacent end portions of the car bodies each having one bolster assigned thereto. To disassemble the construction shown, the pins 34 or either thereof are removed whereupon the adjacent end portions of the car bodies may be elevated a sufficient amount to free the body center bearings from the truck center plates and then the truck may be removed or either body removed from the truck.

The drawing illustrates one embodiment of the invention but it is to be understood that they are for illustrative purposes only and various changes in the form and proportions of the construction may be made within the scope of the appended claims without departing from the spirit of the invention.

What is claimed is:

1. In combination, a plurality of car bodies having their adjacent end portions arranged relatively close together, the adjacent end portions of said bodies being provided with recesses, a truck for supporting the adjacent end portions of said bodies, a pair of truck bolsters arranged side by side and each having a center bearing, body center bearings respectively engaging the truck center bearings, and a restraining element in the before mentioned recesses for preventing excessive relative vertical and sidewise shifting of the bodies.

2. In an articulated car, a plurality of car bodies, body center castings secured to the end portions of said bodies, the forward ends of said castings defining buffering areas, means in said forward ends for preventing excessive relative vertical and sidewise shifting of the bodies, a truck for supporting the adjacent end portions of said bodies, said truck being provided with a pair of bolsters and a pair of center plates, body center bearings depending from the forward ends of said body center castings engaged respectively with the truck center plates.

3. In an articulated car, a plurality of car bodies, body center castings secured to the adjacent end portions of said bodies and arranged in substantially abutting relation whereby to transmit buffering shocks from one body to the other, a truck for supporting the adjacent end portions of said bodies, a pair of bolsters for the truck, center plates carried by the bolsters and with which the body center bearings are respectively engaged, whereby pulling stresses are transmitted from the bodies to the truck, and a bar loosely retained in the adjacent end portions of the body center castings for preventing excessive relative sidewise and vertical shifting of the bodies.

4. An articulated car comprising a plurality of car bodies, body center bearings depending from the adjacent end portions of said bodies, a truck for supporting the adjacent end portions of said bodies having a pair of independent bolsters arranged side by side in relatively close relation, a center plate carried by each bolster and with which the body center bearings are respectively engaged whereby to transmit pulling stresses from the bodies to the truck, a bar extending between and arranged in the adjacent end portions of the bodies for preventing excessive relative sidewise and vertical shifting of the bodies, and pins extending thru the end portions of the bodies and thru the bar into the truck center plates for retaining the bar in position.

5. In an articulated car, a plurality of car bodies having their adjacent end portions arranged in substantially abutting relation to transmit buffing shocks from one body to the other, a truck for supporting the adjacent end portions of said bodies, a pair of bolsters for the truck, each having a center plate, body center bearings engaged respectively with the truck center bearings, and a restraining element extending between and loosely arranged in the end portions of the bodies for preventing excessive relative vertical and sidewise shifting of the bodies.

6. A body center casting comprising a body portion having its forward end reduced to define a buffing area, said forward end being provided with a horizontally arranged recess which increases in width from the rear thereof to the forward end of the casting, and a center bearing depending from and arranged immediately beneath the buffing area.

40 In witness whereof I have hereunto set my hand.

VICTOR WILLOUGHBY.
